ILLUMINATED POST

Harold P. Smith, 1/2 Plains Aluminum Industries,
Box 38, Panhandle, Tex. 79068

Filed Nov. 16, 1966, Ser. No. 4,692

Term of patent 14 years

(Cl. D48—31)

The dominant features of my design reside in the portions shown in full lines.

I claim:

The ornamental design for an illuminated post, as shown and described.
